RESTAURANT SIGN

Charles Laughner, 7719 S. Belmont Road,
Indianapolis, Ind. 46222

Filed July 31, 1972, Ser. No. 276,515

Term of patent 14 years

Int. Cl. D20—03

U.S. Cl. D96—12 R

Fig.1

Fig.3

FIG. 1 is a front elevation view of a restaurant sign showing my new design, the rear being a mirror image thereof.

FIG. 2 is a side elevation view, the opposite side being a mirror image thereof.

FIG. 3 is a top plan view thereof.

The broken line representation of indicia in FIG. 1 is for purposes of illustration only.

I claim:

The ornamental design for a restaurant sign, as shown and described.
